(57) **CLAIM**

The ornamental design for a cake support structure, as shown and described.

DESCRIPTION

FIG. 1 is a front elevational view of a cake support structure showing my new design, the rear elevational view, left side view and right side view being the same thereof;

FIG. 2 is a top plan view thereof;

FIG. 3 is a bottom plan view thereof; and,

FIG. 4 is a perspective view thereof.

The broken lines showing cake layers in FIG. 1 is for illustrative purposes only and forms no part of the claimed design.
